UNITED STATES PATENT OFFICE.

JOHN W. WEAKLEY, OF BOND HILL, OHIO.

COFFEE-POT.

SPECIFICATION forming part of Letters Patent No. 268,061, dated November 28, 1882.

Application filed July 25, 1882. (No model.)

To all whom it may concern:

Be it known that I, JOHN W. WEAKLEY, of Bond Hill, Hamilton county, Ohio, have invented certain new and useful Improvements in Coffee-Pots, of which the following is a specification.

This invention pertains to that class of coffee-pots designed and constructed to return to the decoction the aromatic vapors arising therefrom by condensing them against a cool surface above the vessel containing the decoction; and it consists of a novel arrangement of the condensing apparatus, as hereinafter set forth and claimed.

15 In the accompanying drawings, Figure 1 is a vertical section, and Fig. 2 a plan, of the device.

A is the main vessel, constructed as usual and provided with a handle and lidded spout.

20 O is a deep top section with rim B, fitting well down within the main vessel A, extending to bottom of vessel A, and containing a hole, a, therein, opposite the mouth of the spout, out of which to pour the coffee.

25 G is a diaphragm across the upper portion of the top section, O, forming a water-chamber, F, above it. A hole, L, in the roof or lid K communicates direct with this chamber.

II is a central aperture in the diaphragm C. 30 J is a tube forming a conduit from the aperture H to the interior of the chamber F. This conduit J rises well up into the chamber F, and then descends to a point near the diaphragm F, as shown, so as to form a water-seal in an obvious manner.

35 I is a valve in the tube J, normally closing the aperture H. A stop-wire prevents the valve lifting too far.

D is a diaphragm across the top section, at a 40 point below the diaphragm G, forming between the two diaphragms the condensing-chamber C. The aperture E in the diaphragm D places the

chamber C in communication with the main vessel A.

In operation the coffee decoction occupies 45 the main vessel A. Cold water is placed in the water-chamber F through hole L. This water keeps the condensing-plate G cool, and is prevented from leaving the chamber F by the valve I. The chamber C forms a non-conducting division between the main vessel A and the condensing-plate G, and serves to protect the latter from the direct action of heat previous to the vaporization of any of the liquid in the main vessel. The chamber C, 50 containing air much cooler than the contents of the main vessel, serves to keep the diaphragm D somewhat cool, so that it will act as a preliminary condensing-plate. Vapors uncondensed by the plate D will finally fill the 55 chamber C, be condensed by contact with water-cooled plate G, and run back into the main vessel A through aperture E. Should vapor reach a comparatively high tension, it will lift the valve I and escape into the water 60 in the vessel F. In construction the parts may be arranged to separate for more convenient cleaning.

I claim as my invention—

1. The combination, substantially as set 70 forth, of main chamber A, air-chamber C, water-chamber F, and valve I.

2. The combination, substantially as set forth, of main vessel A, top section, O, seal-rim B, diaphragms D and G, top K, with hole 75 L, and seal-conduit J.

3. The combination, substantially as set forth, of main vessel A, seal-rim B, diaphragms D and G, top K, with hole L, and valve I.

JOHN W. WEAKLEY.
